MEANS FOR FEEDING BELT AMMUNITION
TO HEAVY MACHINE GUNSJohn Dudley North, Wolverhampton, England,
assignor to Boulton Paul Aircraft Limited,
Wolverhampton, England, a British companyApplication May 12, 1942, Serial No. 442,713
In Great Britain February 10, 1939

3 Claims. (Cl. 89—33)

This invention relates to means for feeding belt ammunition to heavy machine guns, that is to say, machine guns which fire projectiles considerably heavier than rifle bullets.

The feeding of ammunition to guns of this type, which may fire at a very rapid rate, particularly when mounted in aircraft, presents special problems. If the cartridges are arranged in magazines or chargers which are clipped on to the top of the breech, there is the difficulty that a charger containing an adequate number of rounds is unduly heavy to be manipulated conveniently in the gun turret. It is therefore desirable to provide a belt feed for such guns. Belt feed on the other hand presents difficulties not met with when rifle ammunition is used owing to the weight and bulk of the individual rounds. Further difficulties arise when it is desired to feed belt ammunition to a gun designed for magazine feed.

In machine guns designed to be fed with ammunition from a belt, the belt feeding means and the means for stripping a round from the belt are provided in the mechanism of the gun itself. For example in one design of rifle calibre machine gun fed from a disintegrating link type belt, the belt is fed to the gun by means of a cam operated lug in the top of the breech casing which engages behind the leading round of the belt and positions this round to be withdrawn from the belt, in the direction of the axis of the round, by means of a claw provided on the leading top edge of the breech block. The link thus freed is pushed into a link ejector chute by the next round as it is fed forward.

Belt feeding and round stripping means are not provided in the mechanism of a magazine fed gun.

An object of the present invention is to provide means for feeding belt ammunition to heavy machine guns designed for magazine feed, comprising a non-disintegrating ammunition belt from which the rounds of ammunition are withdrawn from the side in a direction perpendicular to the longitudinal axis of the round, driving means for the belt and means for stripping the rounds laterally from the belt and pushing them into the breech port of the gun.

A further object of the invention is to lessen any tendency for the rate of fire of the gun to be slowed down by reason of the inertia of the loaded belt which is considerably greater than that of a belt containing rifle calibre ammunition.

A further object is to ensure the accurate

positioning of a round relative to the breech port at the moment of its withdrawal from the belt, irrespective of the angle of elevation of the gun.

With the foregoing and other objects in view, as will hereinafter appear, the invention comprises the novel arrangement and combination of parts hereinafter described and claimed, it being understood that changes in the particular embodiments of the invention, hereinafter described, may be made within the scope of the claims without departing from the invention.

Particular embodiments of the invention are illustrated in the accompanying drawings in which:

- 15 Figure 1 is a side elevation of a belt feed mechanism according to this invention.
- Figure 1A is an extension of the view of Figure 1.
- Figure 2 is an under-plan of Figure 1.
- 20 Fig. 2A is an extension of the view of Figure 2.
- Figure 3 is an end elevation partly in section as seen from the right in Figure 1.
- Figure 4 is an end elevation in section of the line IV—IV in Figure 1A parts being omitted,
- 25 showing a mechanism omitted from Figures 1 to 3.
- Figure 5 is a view similar to Figure 1 showing a modified construction, and
- Figure 6 is an end elevation in section on the line VI—VI in Figure 5.

Referring first to Figures 1 to 4, the gun is indicated at 10, its muzzle being towards the right in Figures 1 and 2 and the loading aperture or breech port 12 in the breech being at one side.

35 The gun is carried in a cradle 14 which is mounted in trunnions, indicated at 16, behind the breech port.

A feed wheel in the form of a chain drum 18 is mounted to rotate on one of the trunnions 16 in needle bearings 20. This drum is provided with teeth 22 to fit the links 24 of a jointed cartridge belt in the manner of a sprocket wheel. Each link is formed with U-shaped guides 26 (Figure 4) to receive the base of a round 28, the open side of the guides being at the side of the chain so that the rounds can be withdrawn from the chain sideways towards the gun. The drum has a flange 30 to which is attached the outer end of a spring 32 of the clock type, the inner end of which is secured to a sleeve 34 mounted to rotate in needle bearings 36 on the hub 38 of the drum 18. The outer face of the sleeve 34 is formed with ratchet teeth 40 cooperating with similar teeth 42 on a driving sleeve 44, the teeth being held yieldingly in engagement by springs

46. The sleeve 34 has a further set of ratchet teeth 48, equal in number to the teeth 22, cooperating with a spring-pressed pawl 50—see Figure 1. The ratchet teeth 40, 42 are so arranged that they engage and drive when the driving sleeve 44 is rotated anti-clockwise as seen in Figure 1, the teeth slipping when the sleeve 44 rotates in the reverse direction.

The driving sleeve 44 carries a radially projecting arm 52 connected to a link 54 reciprocated vertically in synchronism with the operation of the breech mechanism by mechanism to be described hereinafter, and it will be evident that the reciprocation of the link 54 will rotate the sleeve 44 alternately in opposite directions, thereby rotating the sleeve 34 step by step, backward rotation being prevented by the pawl 50.

It will be convenient first to describe the operation of the mechanism as if the drum 18 were fixed to the sleeve 34 (in which case it would of course be rotated positively step by step in the anticlockwise direction) and to explain the function of the spring later. Actually, such an arrangement would be within the scope of the invention in its broad aspect, although the spring confers additional advantages.

As each round reaches the position X (Figures 1A and 3) opposite the breech port 12 it is pushed sideways out of the link and into the breech port by a loading pawl or plunger 56 (Figure 4) which consists of two hook-shaped members fixed to a spindle 58 mounted to rotate in lugs 60 carried by a slide 62 mounted in guides to move towards and away from the breech port transversely to the belt 24. This slide is reciprocated by an arm 64 secured to a shaft 66 which is connected to the device which operates the breech mechanism of the gun (in this case a gas-operated cylinder 68) so that the shaft is oscillated once for each shot fired, the timing being such that each round is pushed into the breech as it comes to the position X. Figure 4 shows the parts near the end of this movement. Before the pawl 56 begins to move back the next round comes into position, the curved hook shape of the pawl allowing of this. The extremities of the pawl are lifted clear of this second round during the backward movement by a resiliently-mounted tongue 70 the tip of which is encountered by a downward extension 72 of the pawl as soon as it begins to move backwards. When the pawl is completely retracted the extension 72 drops into a depression 74 in the tongue 70, thereby enabling the pawl to fall into its former position ready to engage the next round. During the next forward operation the extension 72 depresses the tongue 70 against the action of the spring 76. The pawl may be urged downwards by a spring if desired.

It will be appreciated that if the drum 18 is positively driven there must necessarily be a delay, after the loading of one cartridge into the gun, before the next one comes into the X position because the belt does not begin to move until the driving sleeve 44 has made a step of movement in the clockwise direction, ready for the next feed movement. The function of the spring 32 is to cause the drum 18, and therefore the belt 24, to move immediately each round has been pushed out of the belt, without waiting for the next operation of the ratchet mechanism.

The spring is initially stressed so that it is capable of rotating the drum anti-clockwise in relation to the sleeve 34 to the extent of, say, three rounds and of lifting the loaded belt through 75

that distance. However, it does not have to move the drum more than one step because at the end of each step the round encounters a fixed stop 78 (Figure 4) in the form of an angle bracket inserted immediately above the port 12, which arrests the belt and the drum 18. As soon as this round is clear of the belt the spring immediately brings the next round into position. Immediately afterwards the spring is wound up again by the next step of movement of the sleeve 34, so that the same amount of energy is available for each round.

In an alternative arrangement the spring is wound to an extent sufficient to feed several rounds, or even a complete belt, before being re-wound. If, however, it is re-wound after each step of movement its size is a minimum and therefore the arrangement first described is preferred.

The shaft 66 is urged in the anti-clockwise or loading direction by a spring (not shown) so that if the breech should be closed when it rotates in that direction no damage is done. It is rotated in the clockwise direction by the gas cylinder 68, which has lugs 80 that actuate the breech mechanism through plungers 82. These lugs also rock a two-armed lever 84 connected by a link 86 to an arm 88 secured to the shaft 66. The spring which biases the shaft 66 may be a torsion spring housed within the barrel 90 to which the lever arms 84 are attached. If the breech should be closed when the gas cylinder moves forward (to the right in Figures 1 and 2) all that happens is that the lever 84 does not follow the lug 80.

Referring to Figure 3, the link 54 which drives the sleeve 44 is connected at its upper end to an arm 92 carried by a sleeve 94 rotating on a fixed pivot pin 96. This sleeve carries another arm 98 connected by a link 100 to an arm 102 carried by the shaft 66. Thus the sleeve 44 is oscillated in synchronism with the shaft 66 and therefore with the loading pawl 56. It is to be noticed that the operative movement of the link 54 (the upward movement) is imparted to it by the rearward movement of the gas cylinder, and not by the spring which rocks the shaft 66 in the anti-clockwise direction.

In the example illustrated, in Figures 1 to 4 the gun slides in the cradle 14, recoiling against the action of springs. The bearings for the rear end of the shaft 66 and the spindle 96 are carried by a bracket 104 fixed to the cradle 14. The bearing 106 for the front end of the shaft 66 is, however, fixed to the gun itself and therefore the hub 108 of the arm 88 is splined, as is the end of the shaft 66, to enable these two parts to slide in relation to one another without relative rotation.

Alternatively, the bearing 106 and the supports of the lever 84 may be fixed to the cradle, in which case the lever 84 may be actuated, not by the gas cylinder, but by the recoiling gun itself.

It will be clear that if the cradle and the gun which it carries are elevated above the horizontal each cartridge will be constrained to take up the same angle of elevation as the gun itself as it comes to the loading position; it is always in the same position in relation to the breech port. In some cases the axis of rotation of the feed wheel 18 may be displaced downwards slightly from the axis of the trunnions to compensate for the sagging of the cartridges which causes their axes to be not quite radial to the wheel.

An alternative embodiment of the invention is

illustrated diagrammatically in Figures 5 and 6. In this embodiment the mechanism for pushing the cartridges into the breech port is the same as described above, and is not shown again. The drum 18 is replaced by a roller 180, without sprocket teeth, which is free to rotate around the axis 182 about which the gun is elevated. This roller acts as an arcuate guide for the bases of the cartridges and is made free to rotate merely to reduce friction. If desired, it could be replaced by a fixed guide in the form of a segment of a cylinder. The cartridge belt is in the form of a series of U-shaped clips 240 gripping the cartridges midway of their length and pivoted together by means of ball-and-socket joints 242 to form a chain. The limbs of the loading plunger 56 (Figures 1 and 4) straddle this belt or chain and are therefore able to push the cartridges out of the clips without tilting them.

The belt passes over a sprocket drum 183 the axis of which is parallel to the axis of the gun barrel and which is mounted in bearings carried by the cradle 14. It is driven intermittently by means similar to those described previously in connection with the drum 18.

In order to maintain the bases of the cartridges in contact with the roller 180 when the gun is elevated, a fixed guide plate 184 is provided which is cylindrical and concentric with the roller, and placed so that it just clears the front ends of the cartridges. This guide plate has a straight portion 186 extending downwards from it, and another straight guide plate 188 tangential to the roller 180 is provided to guide the cartridge bases on to the roller. The bases of the cartridges slide up this straight guide 188 and then on to the roller 180. When the gun is used on aircraft, in which the gun barrel may be depressed below the horizontal, the straight guide is tangential to the roller at a point the radius of which makes an angle to the horizontal equal to the greatest angle of depression which is provided for. Lateral guide plates 190, Figure 6, are provided to restrain sideways motion of the belt and to keep it in alignment with the teeth of the sprocket drum 183. These guides enable the gun to be elevated or depressed without interfering with the correct presentation of the cartridges to the breech port.

The guide plates 190 are in the form of circular discs fixed to the gun cradle 14, and the bearings 181 of the sprocket drum 183 are secured to one of these discs, as shown in Figure 6.

What I claim is:

1. Means for feeding belt ammunition to heavy machine guns designed for magazine feed and mounted for rotation about an axis parallel to the direction in which the rounds enter the breech port of the gun, comprising an ammunition belt from which the rounds of ammunition are withdrawn from the side in a direction perpendicular to the long axis of the round, means for feeding the ammunition belt to the breech port of the gun in a plane normal to the axis

of rotation of the gun, arcuate guide means disposed about said axis of rotation for guiding the rounds to a position of correct alignment with the breech port irrespective of the angular position of the gun, a stop located on the gun adjacent the breech port for stopping each round as it reaches said port and a member carried by the gun and normally resiliently urged in a direction to push the round laterally from the belt into said port when the port opens.

2. Apparatus for feeding belt ammunition to heavy machine guns designed for magazine feed and movable in elevation about trunnions, the breech port of the gun being at the side and disposed radially of the axis of said trunnions, comprising a flexible ammunition belt supporting rounds of ammunition by their bases and from which the rounds of ammunition are withdrawn from the side in a direction perpendicular to the longitudinal axis of the round, a feed wheel over which the ammunition belt passes with the rounds of ammunition coplanar therewith, and extending radially therefrom, means for rotating said feed wheel to feed said belt towards the breech port, a stop disposed to engage each round of ammunition as it arrives opposite the breech port of the gun, said feed wheel being mounted co-axial with the gun trunnions so that when a round is engaged by the stop opposite the breech port it is in the correct angular position for entry into the breech, and a member carried by the gun and normally resiliently urged in a direction to push the round laterally from the belt into said port when the port opens.

3. Means for feeding belt ammunition to heavy machine guns designed for magazine feed and mounted for rotation about an axis parallel to the direction in which the rounds enter the breech port of the gun, comprising an ammunition belt from which the rounds of ammunition are withdrawn from the side in a direction perpendicular to the long axis of the round, a feed wheel for feeding the ammunition belt to the breech port of the gun in a plane normal to the axis of rotation of the gun, resilient means for rotating said feed wheel, said resilient means being initially loaded by an amount sufficient to feed a plurality of rounds of ammunition to the gun, arcuate guide means disposed about said axis of rotation for guiding the rounds to a position of correct alignment with the breech port irrespective of the angular position of the gun, a stop located on the gun adjacent said breech port for stopping each round as it reaches said port,

55 a pawl normally resiliently urged in a direction to push the round laterally from the belt into said port when the port opens, said pawl being shaped to permit a fresh round to be moved against the stop by said feed wheel when the 60 first mentioned round has been pushed into the breech port, and means responsive to the firing of the gun to restore the initial loading of said resilient means and to retract said pawl.

JOHN DUDLEY NORTH.
